UNITED STATES PATENT OFFICE.

HENRY A. DIRKES, OF NEW YORK, N.Y.

WINDOW-VENTILATOR.

No. 891,824.

Specification of Letters Patent.

Patented June 30, 1908.

Application filed July 27, 1907. Serial No. 385,790.

To all whom it may concern:

Be it known that I, HENRY A. DIRKES, a citizen of the United States, and a resident of the city, county, and State of New York, have invented certain new and useful Improvements in Ventilation, of which the following is a specification.

This invention relates to certain improvements in that class of ventilators which are particularly designed and adapted for location at the windows and similar openings of buildings and the object of the invention is to provide a device of this general character of a simple and comparatively inexpensive nature and of a strong and compact construction having improved means for the admission of pure and fresh air to the room and also for the simultaneous discharge of the foul or vitiated air therefrom.

20 The invention consists in certain novel features and principles of the construction and combinations and arrangements of the several parts of the improved ventilator, whereby certain important advantages are attained and the device is rendered simpler, cheaper and otherwise better adapted and more convenient for use, all as will be herein-after set forth.

In the accompanying drawings which serve to illustrate my invention—Figure 1 is a sectional view taken vertically through a ventilator constructed according to my invention, the device being shown applied to a window in position for use; Fig. 2 is a sectional view taken horizontally through the device as shown in Fig. 1; Fig. 3 is a sectional view similar to Fig. 2, but showing the casing of the ventilator with its top plate partly broken out to illustrate the interior construction; Fig. 4 is a view showing the lower part of a window having my improved ventilator in place; Fig. 5 is a fragmentary sectional view taken vertically through the front part of the ventilator and showing certain features of construction to be hereinafter described, and Fig. 6 is a view similar to Fig. 2; but showing a modified formation of the device.

In these views 1 represents the window sill and 2 the lower sash, while 3 indicates a board or supporting member of proper dimension to extend across the lower portion of the window opening, with its end portions engaged in the guides 4 of the window casing, its lower edge portion being rested upon the sill and its upper edge portion being adapted to be engaged by the lower edge of the lower

sash rail 2 when said sash is lowered after the ventilator has been placed in position.

5 represents the shell or casing of the improved ventilator, which may be formed from wood, metal or other suitable material held in any preferred way to the central part of the supporting board 3 in such a way that one side of said shell or casing is extended beyond said board 3 at the outer side of the window as shown at 7, while the opposite side of the shell is extended beyond the inner face of the board so as to be within the room to be ventilated as shown at 6^a in the drawings. At opposite ends of the shell or casing 5, the supporting member or board 3 has plates 6, 6, of glass or the like, let into it, in such manner as to obstruct the passage of light as little as possible. This feature of construction, however, forms no part of my invention, and I do not desire to be understood as limiting myself in any way to the use of said transparent glass plates in connection with my improved ventilator, nor to the employment of the supporting board or member 3, since these parts are in no way essential.

The outwardly extended portion 7 of the shell or casing 5 has openings at its opposite ends as shown at 8, and adapted for the entry and discharge of air, screens being extended across said openings in a well known way to prevent the air passages from becoming choked and also to prevent the passage of solid impurities through the ventilator into the building and within the shell or casing is centrally arranged a vertically extended partition 10, whereby the interior of the said shell or casing is divided into two similar, but oppositely arranged compartments or conduits 11, 11, each of which has communication with the external air by way of one of the respective openings 8, 8, at the ends of the outer part 7 of the shell or casing. The partition 10 is extended entirely across the shell or casing so as to entirely separate the respective compartments or conduits 11, 11, from one another, said partition being extended entirely across both the outer and inner portions 7 and 6^a of the casing from the outer to the inner walls thereof so as to be adapted to deliver the air entering the outer part of the casing at one side of the partition through the opening at the top of the inner part of the casing into the room and to similarly deliver the impure air from the room through said opening at the top of the inner

part of the casing, but at the opposite side of the partition 11, so that impure air is discharged from the outer part of the casing in such a way as to prevent escape of the pure air entering by way of one compartment through the other compartment 11, without passing into the room and the inner portion 6^a of the shell or casing, which is extended within the room, is provided with an opening 10 at its top, adapted for the supply and discharge of air to and from the room and to the respective compartments or conduits 11, 11, of the shell or casing. The said opening at the top of the inner part 6^a of the shell or casing is provided with a screen or filter 14, and 15 represents a sliding valve or cover, movable on guides 17 at the ends of the casing and having a handle 16 whereby it may be slid horizontally to more or less close or 20 open the top of said forwardly extended portion 6^a of the casing, air may flow through one or the other of the compartments or conduits 11, 11, dependent upon the direction of the wind, into the room, while at the same 25 time the foul or impure air will be drawn or forced outwardly from the room through the opposite compartment or conduit 11 of the casing, whereby the room may be effectively ventilated as will be readily understood. 30 The valve or cover 15 permits of being adjusted so that the volume of air supplied to and discharged from the room may be effectively controlled to meet varying requirements dependent on temperature and on the 35 situation in which the improved ventilator is employed.

In Fig. 2 I have shown the partition 10 as constructed with opposite inclined or curved faces 12 directed towards the openings 8, 8, 40 at the ends of the casing the movement of the entering and escaping air being facilitated by such curved surfaces as will be readily understood, but I do not desire to be understood as limiting myself to such curved conformation of the partition, since it is evident that a straight partition as shown in Fig. 5 may also be used with good results.

The forward part of the central partition 10 has laterally directed portions 18, 18, at 50 opposite sides of its upper part, as clearly shown in Fig. 5. These laterally directed portions 18, 18, are arranged adjacent to the screen or filter 14, and their lower or under surfaces are reversely curved upwardly and outwardly so as to deflect the air entering the room through one of the conduits or passages by way of one end of the screened opening at the top of the inner part of the casing laterally into the room, 55 whereby such entering air is prevented from passing directly across the top of the screen or filter 14 and escaping by way of the conduit or passage at the opposite side of the central partition.

60 Certain features of construction similar to

those shown in Figs. 5 and 6 are illustrated and claimed in my co-pending application filed June 1, 1908.

From the above description of my invention, it will be obvious that the improved 70 ventilator constructed according to my invention is of an extremely simple and inexpensive nature and is particularly well adapted for use by reason of the effective operation afforded by it in not merely admitting the pure and fresh air but also in the discharging of the foul and vitiated air from the rooms and it will also be evident from the above description that the device is susceptible of considerable modification 80 without material departure from the principles and spirit of the invention and for this reason I do not desire to be understood as limiting myself to the precise form and arrangement of the several parts herein set 85 forth in carrying out my invention in practice. Nor do I wish to be understood as limiting myself to the particular arrangement of the partition or of the conduits or compartments, except that said conduits or 90 compartments are to be completely separated from each other so that the air entering by way of one conduit or compartment will be discharged into the room and is prevented from escaping through the opposite conduit or compartment. Nor do I desire to limit myself to the employment of 95 my improvements in what are termed window ventilators alone, since it is obvious that the invention is well adapted for use 100 in connection with car ventilators and other ventilating devices and systems.

Any variety of register or other controlling means may also be employed where desired, for regulating the flow of air through the 105 conduits to and from the room.

Having thus described my invention, I claim—

1. A ventilator comprising a supporting member adapted to be extended across a 110 window or the like, a casing carried by said member and having portions extended from opposite sides thereof and adapted to be exposed outside and inside of the window, the outside portion of said casing having openings at opposite sides for the admission and discharge of air to and from the interior of the casing, and the inside portion of said casing being also provided with inlet and outlet openings, and a central division 115 extended across the interior of the casing and comprising oppositely arranged parts, the outer ends of which are reversely inclined toward opposite sides of the outside portion of the casing in position to direct the flow of air admitted and discharged at the openings of the said outside portion of the casing, and the inner ends of which are inclined toward each other and are arranged to meet at the central part of the inside portion of the cas-

ing between the respective inlet and outlet openings and forming a partition dividing the interior of the casing into two conduits each adapted for the flow of air.

5 2. A ventilator comprising a supporting member adapted to be extended across a window or the like, a casing carried thereby and having a portion extended from the outside of said member and provided with openings at its opposite sides for the admission and discharge of air to and from the interior of the casing, and having an opening extended transversely across it at the inner side of the supporting member, a division extended 10 across the interior of the casing and comprising parts, the outer ends of which are reversely inclined toward the openings at the outside portion of the casing to direct the air admitted and discharged at the openings at 15 opposite sides thereof, and the inner ends of which are arranged adjacent to each other at the central part of the opening at the inside portion of the casing to divide the same into an inlet and an outlet, and a valve 20 device extended across the transverse opening at the inside portion of the casing and adjustably mounted for movement to open and close the same:

3. A ventilator comprising a casing the 25 outer part of which has openings at opposite

sides and the inner part of which has an opening extended across its top and a vertically arranged partition extended transversely across the interior of the casing and dividing the same into two conduits the outer 30 ends of which are adapted for the admission or discharge of air at the opposite openings at the outer part of the casing and the inner ends of which are adapted for the admission and discharge of air at opposite sides of the 35 opening at the top of the inner part of the casing, the inner end of the partition being extended centrally across the opening in the top of the casing and having at its upper part reversely curved and oppositely directed 40 portions each extended part way across the opening in the top of the casing at the central part of said opening and adapted to deflect the air discharged from the casing at one end of said opening away from the air 45 entering the casing at the opposite end of the opening.

In witness whereof I have hereunto signed my name this 18th day of July 1907, in the presence of two subscribing witnesses.

HENRY A. DIRKES.
